UNITED STATES PATENT OFFICE.

JAMES DOMINIC WHITE, OF ALBANY, NEW YORK.

CYLINDER-LINING FOR ENGINES.

1,361,297.

Specification of Letters Patent. Patented Dec. 7, 1920.

Application filed July 15, 1920. Serial No. 396,397.

To all whom it may concern:

Be it known that I, JAMES D. WHITE, a citizen of the United States, residing at Albany, in the County of Albany and State of New York, have invented certain new and useful Improvements in Cylinder-Linings for Engines; and I do declare the following to be a full, clear, and exact description of the invention, such as will enable others skilled in the art to which it appertains to make and use the same.

This invention relates to improvements in linings for the cylinder bores in the engine block of automobile engines, although it is not to be restricted to this particular use since it may be just as effectively used with various other types of engines.

One of the objects of the invention is to generally improve upon devices of this class by the production of one which is extremely simple and effective and is such that it may be easily and readily inserted and removed.

Another object of the invention is to provide a removable lining for cylinder bores which includes a detachable locking ring which is screw-threaded and engages screw-threads on the lining, this ring having novel means associated with it for positively preventing accidental rotation thereof which would permit displacement of the lining, this means being associated with one or more of the other like rings.

A further object of the invention is to provide a lining of the above mentioned type which is such that it will be prevented against possible movement when properly placed in position thus overcoming wear to which it would be subjected if permitted to move.

Other objects and advantages of the invention will be apparent during the course of the following description.

In the accompanying drawings forming a part of this specification and in which like numerals are employed to designate like parts throughout the same:

Figure 1 is a top plan view of a conventional form of motor block equipped with my improved linings, parts being shown in section.

Fig. 2 is a bottom plan view thereof.

Fig. 3 is a central longitudinal vertical section taken on the line 3—3 of Fig. 1.

Fig. 4 is a transverse section taken on the line 4—4 of Fig. 1.

Fig. 5 is a detail longitudinal view of the lining with the retaining ring removed.

Fig. 6 is a detail sectional view of the retaining ring.

Fig. 7 is an enlarged detail view of the lower end of the lining, showing more clearly the manner in which it coats with the cylinder bore.

In the drawings, wherein for the purpose of illustration, is shown a preferred embodiment of my invention, the letter A designates a portion of a conventional form of automobile engine cylinder block. This block shown is that of a Ford, however, I wish it to be understood that my lining may be used in the bores of various, and probably all types of cylinder blocks including those of steam engines. In order to permit the use of my device, it is necessary to ream the opposite ends of the cylinder bores as shown at S to provide shoulders. Some of the bores may be provided with similar shoulders and it may be unnecessary to form them by reaming as I have suggested above. In addition to providing the bores with these shoulders I also provide them at their upper ends with short vertical slots B, which serve a purpose to be hereinafter set forth. I am assuming that the cylinder block is disposed vertically, hence I may conveniently refer to the "upper" and "lower" ends of the cylinder bore.

My improved lining, designated by the numeral 1, comprises a sleeve of a size to fit snugly in the cylinder bore in the block A, the sleeve being equipped at its upper end with a laterally extending flange 2, the lower face of which is beveled for effective contact with the adjacent shoulder at the upper end of the cylinder bore. Slightly beneath and on one side of the sleeve is a lateral projection or lug 3 which is adapted to extend into the slot B in the wall of the bore for the purpose of preventing rotation of the sleeve. At its lower end, the sleeve is provided with external screw-threads 4 with which the screw-threads of a retaining ring 5 contact, the latter having its inner face also beveled for effective engagement with the beveled shoulder at the lower end of the cylinder bore. In addition to this, it has extending from its lower face, a plurality of closely spaced

apertured projections 6, one of the functions of which is to permit the ring to be rotated for the purpose of tightening and loosening it, this being done with any suitable kind of 5 a tool. These lugs also serve another and extremely important function. To explain, they permit a wire 8 to be passed to the apertures therein and through the apertures in the lugs on one or more of the other rings as 10 illustrated in Fig. 2, the ends of the wire being tied so that relative rotation of the rings will be absolutely prevented. With this construction the linings cannot possibly become displaced or loose enough to interfere with 15 the operation of the piston, which would subject them to considerable wear in case they were loose. Emphasis is to be laid on this feature of construction which is novel and new so far as I am aware. In view of the fact 20 that the retaining ring and lateral flange carried by the lining prevents the latter from moving either up or down, and by provision of the lateral projection 3 which prevents rotation of the lining, it is clear that I have 25 perfected an extremely simple and effective lining which is substantially rigid when in place.

The lining may be either inserted downwardly or upwardly, whichever is desired. 30 However, I have found that the manner shown and described of placing the linings in position is probably the best. It is obvious that in order to insert the lining in the bore, the retaining ring 5 is removed and 35 the screw threaded end of the lining is passed downwardly through the bore and permitted to project beyond the inner end of the lower shoulder. Then, the retaining ring is screwed on and tightened by use of a 40 suitable tool which will be permitted to engage the projections 6 for the purpose of rotating the ring. After two or more of the rings have been screwed on the wire 8 is passed through the apertures in the projection 45 6 in the manner already described in order to prevent relative rotation of the retaining rings, thus locking them in effective position and preventing accidental rotation which might otherwise occur.

50 From the foregoing description it will be seen that I have devised an extremely simple, effective, and inexpensive method of keeping the cylinders of a motor car in perfect condition with very little cost to the 55 owner of the car. My linings provide a remedy for insuring excellent compression which is lost in worn cylinders which must necessarily be re-bored in order to secure this result. Re-boring of the cylinders is a 60 difficult and expensive operation and the replacing of a new motor block is likewise expensive and when the cylinders are re-bored a whole new set of over-sized piston rings and pistons must be supplied which 65 of course adds to the expense. By the pro-

vision of my novel, simple and inexpensive removable lining, these disadvantages and expensive operations are entirely overcome. In case the linings become badly worn, they may be easily and readily removed and new ones installed. Hence, effective operation of the engine is insured at all times by employing these removable linings. 70

A careful consideration of the foregoing 75 description taken in connection with the accompanying drawings will enable persons skilled in the art to which this invention appertains, to obtain a clear understanding of the same. Therefore, a more lengthy description is deemed unnecessary. 80

Since probably the best results may be obtained with the construction and arrangement shown, this is to be taken as a preferred embodiment of my invention. However, I wish it to be understood that minor changes in the shape, size, and arrangement of parts may be resorted to without departing from the spirit of the invention 85 or the scope of the subjoined claims. 90

I claim:

1. In a removable cylinder lining for engines, the combination with an engine block provided with a cylinder bore in the wall of which is a vertical groove and at the opposite ends of which are shoulders, of a lining fitted into the bore, provided with a laterally extending lug fitting into said groove, and at its ends with lateral flanges engaging said shoulders, one of said flanges being detachable to permit insertion and removal of the lining. 95

2. In a removable cylinder lining, the combination with an engine cylinder block provided with a cylinder bore beveled at its opposite ends to provide shoulders; of a removable lining fitted into the bore, the same being provided at one end with a lateral beveled flange engaging the upper shoulder and being screw threaded at its opposite ends, an internally screw-threaded beveled ring engaging said threaded end of the lining, and coacting means between the latter and the wall of said bore to prevent rotation of the lining. 100 105 110

3. In an engine cylinder lining, the combination with a cylinder block provided with a vertical cylinder bore having shoulders at its opposite ends, a sleeve disposed in the bore, being provided at one end with a shoulder engaging said first shoulder, and at its opposite end with screw-threads, a screw-threaded retaining ring fitted on the screw-threaded end of said sleeve and engaging the adjacent shoulder on the cylinder block, said ring having a plurality of closely spaced lateral projections thereon by means of which it may be rotated. 115 120 125

4. In an engine cylinder lining, the combination with a cylinder block including a 130

plurality of cylinder bores having shoulders at one end, linings fitted into said bores, being screw-threaded at one of their ends, co-acting means between their opposite end 5 and said bores for retaining them against movement in one direction, screw-thread rings engaging the threaded ends of said sleeves, said rings carrying a plurality of

laterally extending apertured lugs for rotating them, and a wire passing through the 10 apertures in said lugs to lock said rings against relative rotary movement.

In testimony whereof I have hereunto set my hand.

JAMES DOMINIC WHITE.
